(71) Applicant: **GETAC TECHNOLOGY CORPORATION**, Hsinchu County (TW)

* cited by examiner

(72) Inventor: **Chun-Hsing Li**, Taipei (TW)

Primary Examiner — Catherine R Oliver-Garcia

(73) Assignee: **Getac Technology Corporation**, Hsinchu County (TW)

(57) **CLAIM**

The ornamental design for a holder for portable electronic device, as shown and described.

(**) Term: **15 Years**

DESCRIPTION

(21) Appl. No.: **29/595,158**

FIG. 1 is a top front left perspective view showing a first embodiment of my new design;

(22) Filed: **Feb. 25, 2017**

FIG. 2 is a top rear right perspective view thereof;

(51) **LOC (11) Cl.** **03-01**

FIG. 3 is a front view thereof;

(52) **U.S. Cl.**

FIG. 4 is a rear view thereof;

USPC **D3/218**

FIG. 5 is a left side view thereof;

(58) **Field of Classification Search**

FIG. 6 is a right side view thereof;

USPC D3/218-219, 215, 201, 269, 247;

FIG. 7 is a top view thereof;

224/183, 269, 242, 271, 666, 669, 670,

FIG. 8 is a bottom view thereof;

224/930, 196; 206/305, 320; 24/3.11,

FIG. 9 is a reference perspective view of the first embodiment of my new design installed on a portable electronic device;

24/3.12; 455/575.1-575.8; D14/248, 250

FIG. 10 is a top front left perspective view showing a second embodiment of my new design;

CPC A45F 5/00; A45F 5/02; A45F 2005/026;

FIG. 11 is a top rear right perspective view thereof;

A45F 2200/0508; A45F 2200/0516; A45F

FIG. 12 is a front view thereof;

2200/0525

FIG. 13 is a rear view thereof;

See application file for complete search history.

FIG. 14 is a left side view thereof;

(56) **References Cited**

FIG. 15 is a right side view thereof;
